UNITED STATES PATENT OFFICE.

THOMAS A. BRIGGS, OF EAST GREENWICH, RHODE ISLAND, ASSIGNOR
TO BOSTON WIRE STITCHER COMPANY, OF EAST GREENWICH, RHODE
ISLAND, A CORPORATION OF MAINE.

STAPLE-MAGAZINE.

No. 836,662.

Specification of Letters Patent.

Patented Nov. 20, 1906.

Original application filed June 12, 1905, Serial No. 264,794. Divided and this application filed October 16, 1905. Serial No. 282,933.

To all whom it may concern:

Be it known that I, THOMAS A. BRIGGS, of East Greenwich, in the county of Kent and State of Rhode Island, have invented certain 5 new and useful Improvements in Staple-Magazines, of which the following is a specification.

This invention relates to machines for applying staples to attach sheets of paper, &c., together, such as illustrated, described, and claimed in my application filed June 12, 1905, Serial No. 264,794, of which this present application is a division.

The object of this present invention is to 15 provide a novel detachable staple-holder for use in connection with a machine for applying staples of any preferred form, but particularly of the form shown in my application Serial No. 264,794, referred to, said staple-holder being capable of being readily attached 20 to the machine, which is loaded with staples previously to its attachment and which may be removed, if necessary, when only a part of the staples have been fed therefrom to the 25 action of the stapling devices without losing the remaining staples carried thereby.

To these ends my present invention consists of the novel staple-holder or package of staples, substantially as hereinafter described 30 and claimed.

Of the accompanying drawings, Figure 1 represents a side elevation of so much of the upper part of a stapling-machine having my improved staple-holder applied thereto as is necessary to illustrate the utility of the said 35 staple-holder. Fig. 2 represents a sectional view on line 2 2 of Fig. 1. Fig. 3 represents a vertical section on line 3 3 of Fig. 1 looking toward the right. Fig. 4 represents a side elevation of the detachable staple holder or 40 container. Fig. 5 represents a sectional view of the same on line 5 5 of Fig. 4 looking toward the right. Fig. 6 represents a section on line 6 6 of Fig. 4 looking toward the left. Fig. 7 represents a plan view of the staple- 45 feeder which pushes the staples from the container into position to be acted on by the driver.

The same reference characters indicate the 50 same parts in all the figures.

So much of the stapling-machine as is necessary to illustrate herein comprises a standard, a portion of which is indicated in Fig. 1

at 3, to which standard a work-support 4 and staple-clenchers are attached. A portion of 55 a post 5, also forming a part of the frame of the machine, has pivoted thereto at 6 an arm 7, extending laterally in the direction of the standard 3, and the forward end of which is above the work-support 4. In the end of 60 the arm and directly above a staple-receiving throat in the work-support is a guideway 8, which receives a driver 9, movable therein toward and from the work-support. The guideway is located between a flange 10 of 65 the arm and an end plate 11, being preferably formed wholly in the plate.

A bell-crank lever 12, pivoted to a lug 13, extending from the arm 7, is detachably engaged with the driver by means of a link 14 70 and when oscillated causes the driver to be moved in a substantially vertical line toward and from the work-support.

I will now proceed to describe the particular features which are embodied in the claims 75 of this application.

The staples to be driven are held by a novel container or magazine, which consists of a rigid bar having an approximately rectangular cross-section of such dimensions that 80 staples placed on the upper surface thereof may rest with their legs hanging down on each of the sides. The bar, which is represented by the the numeral 48, may be made of any desired material, but is preferably of 85 wood, as that is the substance which can be most easily worked and also has the necessary stiffness. The bar, having a series of staples packed closely together, is covered with a surrounding layer of paper, which securely holds 90 the staples on the bar and prevents their being dislodged. Flanges 49, formed on the bar just below the ends of the staples and projecting on each side a distance approximately equal to the thickness of the wire forming the 95 staples, hold the covering 50 somewhat away from the sides of the staples, so that they can be readily pushed along the bar within the covering. The staple-holding bar 48 is applied in a substantially horizontal position to the arm 7, one end thereof passing through an opening in flange 10 into close proximity with the guideway 8, while the outer end is held by a movable retainer 51, which slides through a passage 52 in the rear extension 31 100 of the arm and has a reduced extremity 53,

which enters an orifice in the end of the bar and is surrounded by a shoulder which abuts against the end surface of the bar.

As the passage or guideway 8 in which the 5 driver travels is of sufficient width to admit a staple fed from the staple-holder and as the bar 48 is of less width than the staples, it is necessary to provide means for preventing the end of the bar extending across and obstructing the guideway. Means for performing this 10 function is provided in the abutment 54, consisting of a plate mounted in a horizontal guide 55 in the arm and of such width that when projected toward the end of the arm it engages the face-plate 11 on either side of the passage-way 8, and so bridges the passage-way. This bridging-abutment has an upwardly-projecting lug 56, located so as to engage the end of the bar 48 and hold it out of the guideway. 15 It will be seen from the foregoing that the staple-holder is thus securely held in position with one end where staples can be pushed forward beneath the driver and that it can be easily removed and a new one substituted by 20 25 simply withdrawing the retainer 51 and slipping out the staple-holder.

Since the paper covering remains on the staple-magazine after the same is attached to a machine and as long as any staples remain 30 on the magazine, it has a condition of permanence and may be called a "permanent" covering. When the paper is pasted to the body portion of the holder, the fragments remain thereon, even after it has been torn from end 35 to end and all of the staples removed.

For feeding the staples into the guideway there is provided a pusher 57, having a shape and dimensions in cross-section corresponding to those of the staples and adapted to be 40 placed upon the bar 48 in the same manner as the staples. It has a central horizontal portion 58 and side portions 59, bent downwardly to embrace the sides of the bar, and also an upward projection 60, formed as a 45 hook, which may be engaged by any suitable means and by which the feeder may be impelled along the bar, pushing the staples as it comes along the bar and forcing them one by one into the guideway. The forward edge 50 55 of the hook 60 is made in such form as most readily to cut or break the upper surface of the paper covering 50 to permit its motion, and to facilitate this result the paper may be previously partly cut on a line of indentations or perforations 62. The feeder shown in the drawings is provided near its rear end with inwardly-turned flanges 63, extending toward each other from the side portion 59 of the feeder and adapted to extend 60 into grooves 64 in the sides of the bar to hold the rear portion of the feeder down upon the bar and prevent its being elevated by pressure applied to the hook 60. These flanges, however, are not always essential. The 65 pusher may be made of any desired material

and in any manner; but preferably it is cut from a single piece of sheet-steel and portions to form the upward projections, the sides, and the flanges bent away from the central portion in the required manner.

70

A spring 65 is provided for producing a continuous pull, tending to move the feeder toward the driver, one end of the spring being formed with a loop, which is slipped over the hook 60, the spring being then carried 75 over a pulley 66, and its other end being connected to the retainer 51, which is offset to permit its attachment. It will be seen that this arrangement permits a single spring to be used for holding the retainer in engagement with the bar and also for actuating the feeder, and that thus equal pressures are produced upon these members.

75

I do not claim herein any of the parts of the stapling-machine itself, as the same form 80 the subject-matter of claims in the application above referred to and of which application this is a division.

I claim—

1. A staple holder or magazine comprising 90 a body portion forming a support and guide for a series of staples, and an envelop extending over the staples, arranged to retain the latter on the body portion while permitting movement of the staples longitudinally 95 thereof.

2. A staple-magazine comprising a body portion constructed to hold staples, and an envelop held on said body portion and extending over the staples adapted to retain 100 them on the body portion against lateral displacement, and to permit removal of the staples longitudinally of the body portion.

3. A package of staples adapted to be applied to a stapling-machine, comprising a 105 holder having a cross-sectional outline corresponding to the form of a staple, a series of staples arranged on and embracing the holder, and a covering surrounding the staples, inclosing the legs of the latter, retaining 110 the staples in place, and free at the ends of the holder to permit feeding of the staples.

4. A package of staples comprising a rigid 115 body portion adapted to be attached to a stapling-machine, a series of staples partially surrounding the body portion and carried thereby, and a flexible covering wrapped laterally about the staples and secured to the body portion between the ends of the latter.

5. A package of staples comprising a rigid 120 body portion adapted to be attached to a stapling-machine, a series of staples partially surrounding the body portion and carried thereby, flanges projecting from the sides of the body portion adjacent the ends of the 125 staples, and a flexible covering passing about the staples and secured to the body portion, said flanges serving to hold the covering away from the legs of the staples.

6. A staple - magazine comprising a body 130

portion constructed to hold staples, and a wrapping inclosing the staples to retain them on the body portion, said body portion having provisions for receiving and guiding a pusher.

7. A staple-magazine comprising a body portion constructed to hold staples, and a covering inclosing the staples and the sides of the body portion, secured to the body portion.

8. A staple holder or magazine comprising a body portion adapted to support a series of staples, and a permanent retaining-covering made of material which can be easily torn.

9. A staple holder or magazine adapted for attachment to a stapling-machine comprising a body portion adapted to support a series of staples, and a retaining-covering of paper attached to the body portion and arranged to remain in place when the holder is in operative relation with a stapling-machine.

In testimony whereof I have affixed my signature in presence of two witnesses.

THOMAS A. BRIGGS.
